TIP FOR WEFT DETECTORS

Oscar V. Payne, Leicester, Mass., assignor to
Crompton & Knowles Loom Works, Worcester,
Mass., a corporation of Massachusetts

Application August 31, 1934, Serial No. 742,258

8 Claims. (Cl. 139—287)

This invention relates to improvements in feeler tips for weft detectors and it is the general object of the invention to provide a detector having improved wearing qualities coupled with smooth contacting surfaces which will not abrade the yarn being detected.

In the type of weft detector to which my invention particularly relates there is an arm having a surface with weft penetrating elements which sink into a working supply of yarn and are held against lateral movement, but when the weft is exhausted the elements slide along the bare bobbin to initiate a change in loom operation. As heretofore made the penetrating elements have been in various forms, such as teeth cut in metal or fiber, but when used in certain types of yarn undesirably rapid wear results. It is an important feature of my present invention to use a wire to form the penetrating elements of the detector, the wire having a surface which is smooth and hard and therefore capable of resisting wear when used with hard yarn.

With certain types of yarn it is desirable that the detector arm be as light as possible to reduce the force of the blow accompanying each detecting operation and I accordingly make the carrier for the detector surface a light wire of small dimensions. In order that the proper diameter of coils may be provided I surround a portion of the carrier wire with a barrel having a diameter sufficient to accommodate spring coils of a proper size.

The spring has two free ends which will abrade the weft being detected unless guarded and it is a further object of my present invention to provide a carrier for the spring such as the previously mentioned barrel, shaped to guard the ends of the spring. In order that the barrel may not rotate on the carrier wire I curve the barrel after it has been applied to the carrier wire, thus holding the free ends of the spring on the forward part of the barrel where they cannot have engagement with and damage the surface being detected. The curving of the barrel together with the disposition of the coils of spring along a curved line results in improved detecting operation.

It is a further object of my invention to provide for holding the spring on the barrel in such a way as to prevent longitudinal and rotational movement thereof on the barrel. This result may be achieved by providing notches or recesses in the barrel for the bent ends of the spring.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a plan view of a detector employing my improved tip,

Fig. 2 is a portion of Fig. 1 on an enlarged scale,
Fig. 3 is a vertical section on line 3—3 of Fig. 2,
Fig. 4 is an enlarged vertical section on line 4—4 of Fig. 3,

Fig. 5 is a horizontal section on line 5—5 of Fig. 3, and

Figs. 6 to 10 represent diagrammatically one method of making my improved detector tip.

Referring particularly to Fig. 1, I have shown a bracket 20 supported by the loom frame not shown and carrying a weft detector D having a housing 21 in which is mounted a slide 22 for back and forth motion. A detector arm 23 is pivoted as at 24 to the slide and has a forwardly extending tail 25 held against a stop 26 on the slide by a spring 27 located in the housing. The spring bears against a part of arm 23 and serves the dual purpose of holding the detector arm 23 in normal angular position with respect to the slide and also keeping the latter in normal rearward position. An upturned end 28 of the slide may if desired form a stop to limit rear motion of the detector and may also be the means for withdrawing the feeler arm on transferring beats of the loom.

A controller 30 is located for cooperative relation with the tail 25 and normally clears an actuator lever 31 having a downward motion each detecting beat of the loom. The actuator moves in a guide 32 and when uninterrupted effects no change in the loom, but when the controller is moved to the left by tail 25 it holds up the actuator and a change will result, such as stoppage or replenishment. The matter thus far described may be as set forth in my prior Patent No. 1,738,193 and of itself forms no part of my present invention.

In carrying my present invention into effect I secure to the rear part of detector arm 23 a carrier wire 40 which extends rearwardly and is bent slightly to have a section 41 terminating in a bend 42. The wire then extends through a barrel 43 and is rebent as at 44 and has a straight part 45 extending into proximity to or in actual engagement with the wire 40.

The barrel 43 may originally be of cylindrical form and is provided near its ends and on the same side thereof with flat slabbed surfaces 46 which define recesses 47 having shoulders 48 shown particularly in Figs. 4 and 5. That part of the barrel diametrically opposite the pockets may be cylindrical and the barrel is preferably curved, as suggested in Fig. 2, so that the notches or recesses 47 are on the inner side of the curve and on the front of the barrel.

The detector teeth are provided by the coils of a spring 50 the normal diameter of which is preferably slightly less than the external diameter of

the barrel 43. The spring is expanded before application to the barrel and when released contracts to grip the same so that there is no appreciable relative movement of the coils either 5 along the barrel or back and forth with respect to each other. I find it desirable to maintain the coils in a definite relation with respect to the pivot 24. This relation may be effected by the adjustment provided for by the bolt 29 which passes 10 through the housing of the detector and the bracket 20.

A method of forming my improved detector tip is set forth in Figs. 6 to 10. In Fig. 6 the barrel is shown as being straight and the carrier wire 15 40 ready to enter bore 55 of the barrel. The wire is then passed through the bore and extended beyond to the right, as shown in Fig. 7, after which the spring 50 is placed over the barrel, as suggested in Fig. 8. The ends 51 of the spring may 20 then be bent up so as to be confined within the notches 47 and preferably in engagement with shoulders 48, as suggested in Fig. 4, after which the barrel and the wire passing through it are jointly bent so that the notches are on the inside 25 of the bend, to assume the shape suggested in Fig. 9. Thereafter the parts 41 and 45 are bent toward each other to assume a position shown in Fig. 10 which corresponds to the structural showing of Figs. 1, 2 and 5.

30 I preferably form the bends 42 and 44 as near the ends of the barrel as possible so that the latter will have no opportunity to slide along that part of the wire 40 which it surrounds.

In operation, a working supply of weft will 35 be penetrated by the spring coils and slipping along the surfaces being detected will be prevented. When the bobbin B is practically empty so that only a very small amount of weft W remains, as shown in Fig. 1, the coils of the spring 40 will slide along the bobbin to give the indication previously described.

The wire of which the spring is formed may be 45 made of any desired size depending upon the character of yarn being detected and as light as is consistent with requisite strength. The proper diameter of the coils is determined by the diameter of the barrel 43 which is comparatively short and adds little to the weight of the moving parts of the detector. The shoulders 48, by their engagement with the ends of the spring, prevent the latter from longitudinal motion along the barrel.

50 From the foregoing it will be seen that I have provided a very simple form of detector tip comprising a spring surrounding a barrel mounted on a carrier wire and larger than the latter. The coils of the spring are held to the proper diameter by the barrel. The latter is also provided with recesses or notches which receive the free ends 55 of the spring, and the bend or curve of the barrel 60 is such that these ends of the wire can never engage the surface being detected. Furthermore, the ends of the spring as shown in Figs. 4 and 5 are preferably so disposed with respect to adjacent parts of the barrel that no yarn lying across 65 the feeler tip will have an opportunity to catch on said ends. Also, the spring is held against longitudinal motion on the barrel by shoulders 48, and the barrel is placed definitely by bends 42 and 44 of the carrier wire, so that the coils of 70 the spring are maintained in correct position with respect to the pivot 24.

Having thus described my invention it will be seen that changes and modifications may be made therein by those skilled in the art without departing 75 from the spirit and scope of the invention and

I do not wish to be limited to the details herein disclosed, but what I claim is:

1. A tip for a weft detector comprising a supporting barrel held against rotation and formed with recesses in the front part thereof, and a coiled spring having coils extending around the barrel to present detector teeth and having the ends thereof located in the recesses. 5

2. A tip for a weft detector comprising a curved barrel, and a curved carrier wire extending through and supporting the barrel, and a coiled spring on the barrel having the ends thereof terminating on that side of the barrel opposite the part which engages the surface being detected and on the inside of the curve of said barrel. 10

15 3. A tip for a weft detector comprising a carrier wire having a part thereof curved, a barrel surrounding the curved part of the wire and partaking of the curve of said part, and a coiled spring on the barrel having the coils thereof arranged as detector teeth along the curved barrel and having the ends thereof held out of engaging position relatively to the surface being detected, rotation of the barrel being prevented 20 by the curvature of said wire and barrel. 25

30 4. A tip for a weft detector comprising a curved barrel held against rotation and having recesses therein, and a coiled spring surrounding said barrel and having the ends thereof located in the recesses to prevent slipping of the spring along the barrel, said recesses and ends of the spring being located on the side of the barrel opposite the part engaged by the weft during a detecting operation. 35

35 5. A feeler tip for a weft detector comprising a carrier wire, a barrel, part of the wire extending through the barrel and together with the latter being curved to have a convex surface toward the surface being detected, other parts of the carrier wire being bent forwardly from each 40 end of the barrel, and a coil spring surrounding the barrel and having the coils thereof serving as detector teeth and having the ends thereof terminating adjacent the concave side of the curve of the barrel. 45

45 6. A tip for a weft detector comprising a curved barrel having a curved bore therethrough, a carrier wire extending through the bore, the portions of the wire adjacent the ends of the barrel being bent forwardly to prevent substantial longitudinal movement of the barrel along the part of the wire extending through the bore and a coil spring surrounding the barrel and gripping the latter by the resilience of the coils thereof and having its ends located on that side of the barrel opposite the latter part which engages the surface to be detected, the barrel and spring being held against longitudinal movement relatively to the carrier wire. 50

55 7. A tip for a weft detector comprising a barrel held against rotation and having recesses defining shoulders transverse of the longitudinal axis of said barrel, and a coil spring surrounding the barrel and having the ends thereof terminating in the recesses and positioned to engage the 65 shoulders to prevent longitudinal movement of the spring along the barrel. 60

70 8. A tip for a weft detector having a barrel held against rotation, shoulders formed on the barrel disposed transversely of the axis of the latter, and a coil spring surrounding the barrel and having the ends thereof bent to have engagement with the shoulders to prevent longitudinal movement of the spring along the barrel. 75
